his Attorney.

UNITED STATES PATENT OFFICE

2,353,849

TUYÈRE FOR BLAST FURNACES
AND THE LIKE

Alan H. Richardson, Edgewood, Pa.

Application August 27, 1941, Serial No. 408,525

2 Claims. (Cl. 122—6.6)

This invention relates to tuyères and bosh plates and, particularly, to an improved tuyère for use in blast furnaces and the like.

Tuyères such as are used in blast furnaces project a short distance into the furnace and are subjected to extremely high temperatures and considerable wear. Heretofore, such tuyères had a relatively thin-walled nose and the metal at the nose was oftentimes not sufficient to withstand the abrasion and burning which are characteristic conditions at that location in a blast furnace. That is, tuyères constructed with a thin nose had a relatively short life, due to the failure of the metal of the tuyères at this point.

Thick-walled tuyères are usually made of cast copper, aluminum, or steel and shrinkage segregation of the metal oftentimes takes place in the nose portion of the tuyère during the casting thereof, thereby resulting in a weak-walled nose portion which does not have a sound metal structure. Such tuyères oftentimes fail under pressure test inspection due to such shrinkage porosity.

While tuyères having a relatively thick nose portion have been heretofore suggested and used, none of these tuyères provided means therewith for taking care of such contraction of the metal in the nose portion thereof, during solidification of metal while the tuyères were being cast. Consequently, these heavy nose portions contained shrink cavities and internal stresses which were produced by the prior solidification and contraction of the relatively thin side walls of the tuyère. That is to say, the prior solidification of the side walls and other portions of the tuyère caused shrinkage segregation and stresses within the relatively heavy section of the nose.

In the present invention, there is provided a tuyère not only having a relatively thick nose portion but, in addition, having means or other heavy structural portions arranged therewith so as to provide a volume of metal to replace that in the nose which is lost by shrinkage during solidification thereof, thereby eliminating the above named disadvantages.

Accordingly, it is one of the objects of the present invention to provide an improved tuyère having a thickened nose portion of uniformly dense metal structure, thereby reducing the danger of the failure thereof to a minimum.

It is another object of the invention to provide an improved tuyère having a thickened nose portion and having means arranged therewith for feeding the metal thereto during the contraction and solidification thereof, while the tuyère

is being cast so as to eliminate any internal stresses and shrinkage cavities therein.

It is a further object of this invention to provide a water-cooled tuyère in which the heat absorbed by the nose portion will be rapidly dissipated therefrom.

It is still another object of the present invention to provide an improved tuyère which is simple and inexpensive, as well as strong and rugged, in its construction.

Various other objects and advantages of this invention will become more apparent during the course of the following specification and will be particularly pointed out in the appended claims.

In the accompanying drawing there is shown, for the purpose of illustration, one embodiment which my invention may assume in practice.

In the drawing:

Figure 1 is a longitudinal section through the improved tuyère of my invention; and

Figure 2 is a section taken on line II—II of Figure 1.

Referring more particularly to the drawing, the improved tuyère of my invention consists of a hollow cylindrical cast copper body member 2 having a tapered outer side wall 3. There is arranged within the body member 2, and integral therewith, a substantially straight cylindrical inner portion or wall 4 which is spaced from the inner side of the side wall 3 so as to provide an annular cooling chamber 5 around the body member between the inner wall 4 and the outer side wall 3.

The ends of the cylindrical inner portion 4 are 35 permitted preferably to remain open so as to provide a hollow central chamber or opening 6 therethrough for conducting the blast. The annular chamber 5 at the larger end of the body member is closed by an end wall 7 having a plurality of 40 threaded openings 8 arranged therein to which suitable pipes are adapted to be connected for conveying a cooling medium into and through the annular chamber 5. The opposite end of the annular chamber 5 at the smaller end of the body member 2 is closed by a nose portion or wall 9 having a smooth outer surface.

According to the present invention, the nose portion 9 is relatively thick with respect to the outer side walls 3, as shown in Figure 1 of the drawing, and preferably has a thickness of about one and one-half inches. There is arranged on the inner side of the nose portion 9, integral therewith and extending inwardly of the body member, a plurality of spaced apart portions 10, or risers or feeders, as they are sometimes called,

and are preferably cylindrical or truncated conical in shape. The portions or risers 10 are arranged concentrically with the axis of the tuyère or body member and substantially parallel to the outer side wall 3 and the inner wall 4 and are spaced therefrom. The portions or risers 10 are preferably from about two inches to four inches in length and have a diameter at their base of about three-quarters of an inch and taper inwardly so as to have a slightly smaller diameter on the inner or free end thereof.

When the tuyère is in use, a cooling fluid, such as water, is adapted to be circulated into and around the annular chamber 5 and around the inwardly extending portions or risers 10 arranged therein so as to dissipate the heat absorbed by the nose portion 8 whereby the same is maintained at a reduced temperature at all times.

It will be understood that the tuyère of the present invention is adapted to be made from cast copper, aluminum, steel or other metals. During the casting thereof, the metal in the thickened nose portion 8 shrinks and it is the primary purpose in providing the inwardly extending portions or risers 10, so that the metal therein will feed into the nose portion 8 as it contracts and shrinks during the cooling thereof so as to prevent shrinkage cavities from being formed therein. That is, the risers or feeders 10 are primarily provided to control the internal segregation and porosity of the nose portion of the tuyère during the casting thereof and are preferably located directly opposite the relatively heavy nose section in order to provide a volume of metal to replace that which will be lost by shrinkage or solidification of the metal in the nose portion.

As a result, by providing the inwardly extending portions or risers 10, there will be provided a more dense grain structure in the nose portion of the tuyère and a relief of the internal stresses existing at the juncture of the side wall and the nose section of the tuyère and, consequently, a structure less susceptible to cracks which are caused by thermal or mechanical shocks. Also, it will be seen that the inwardly extending por-

tions or risers provide a means for increasing the density of the metal in the nose and, hence, an improved rate of heat conduction within the tuyère, and that there is provided a nose portion having improved wear and pressure-resistant qualities.

While I have shown and described one specific embodiment of my invention, it will be understood that this embodiment is merely for the purpose of illustration and description and that various other forms may be devised within the scope of my invention, as defined in the appended claims.

I claim:

1. A tuyère of the class described comprising a hollow body member having an outer wall, an inner wall arranged within said body member so as to provide an annular cooling chamber there-around between said inner and outer walls, said body member having an opening arranged in one end thereof for conveying a cooling fluid thereinto, a relatively thick-walled nose portion arranged on the opposite end of said body member, said outer and inner walls and said nose portion of said body member being integrally arranged and consisting of a casting, and a plurality of spaced apart risers having a greater cross-sectional thickness than the walls of the tuyère arranged annularly around said nose portion integral therewith and extending into said annular chamber between said inner and outer walls and being spaced therefrom, said risers being of sufficient thickness to provide metal to the nose portion of the body member during the contraction and solidification of the metal thereof while casting the same so as to eliminate internal stresses and shrinkage cavities therein whereby a uniform dense metal structure is provided in the thick-walled nose portion of the tuyère which is highly resistant to abrasion.

2. A tuyère of the class described as defined in claim 1 wherein each of the risers tapers inwardly toward the opposite end of the body member.

ALAN H. RICHARDSON.
